UNITED STATES PATENT OFFICE.

ARNOLD STUCKI, OF ALLEGHENY, PENNSYLVANIA.

BUSHING FOR RAILWAY SCREW-SPIKES.

No. 843,713.

Specification of Letters Patent.

Patented Feb. 12, 1907.

Application filed February 18, 1906. Serial No. 300,937.

To all whom it may concern:

Be it known that I, ARNOLD STUCKI, a resident of Allegheny, in the county of Allegheny and State of Pennsylvania, have invented a new and useful Improvement in Bushings for Railway Screw-Spikes; and I do hereby declare the following to be a full, clear, and exact description thereof.

This invention relates to a sleeve or bushing to be inserted in railway cross-ties for receiving a screw-spike. The object, generally stated, is to provide a device of this character which will prolong the life of the tie, which is cheap to manufacture, and which will securely hold the rail-fastening means.

Ordinary railway-spikes when driven in wooden ties possess only a small holding power in the wood, are likely not to hold the track exactly to gage, break the fiber of the wood, and also permit water to enter the hole formed by the spike. As a consequence, the tie is rapidly destroyed, both chemically, due to the action of the water, and mechanically, due to the pounding of the rail thereon on account of the slip of the spike in the wood. Resort has been made to tie-plugs and spike-bushings for the purpose of overcoming the evils of the track being out of gage and the water entering the wood; but these only partially prevent the evil. Screw-receiving bushings or sleeves have also been resorted to; but, as far as I know, these comprise either a sleeve formed from a spiral wire or threaded or unthreaded wooden bushing.

The first-named is too expensive to make and to apply, the second does not possess the requisite strength, and the third is not held in the wooden tie with sufficient firmness to do much good.

My invention is intended to provide a device of the above kind which is efficient, cheap to construct, and which will overcome all of the disadvantages above named. The invention consists of a metal sleeve threaded internally for receiving the screw-spike and having at its upper end a flange, said sleeve being adapted to be driven into a countersunk hole formed in the tie and to rest on the bottom of the hole as well as on the shoulder formed by the countersink, thus giving a firm support to the rail-plate and, on account of its comparatively large diameter, exerting a strong frictional grip in the wood.

In the accompanying drawings, Figure 1 is a vertical section through a rail and tie, showing my device applied thereto. Fig. 2

is a similar view showing a modification, and Fig. 3 is a plan view of the sleeve or bushing.

In the drawings the rail is shown at 1 provided with the usual base-flanges 2 and resting on a tie-plate 3 of the usual construction. The tie 4 will have bored into it an opening 5, provided at its upper end with a countersink 6, in which opening will be driven the sleeve or bushing 7. Said sleeve is threaded internally, as at 8, for receiving the screw-spike 9.

The sleeve 7 is a solid metal sleeve having a closed bottom 10, which rests upon the bottom of the hole in the tie and at its upper end is provided with a flange 11, which fits in the countersink 6 and rests upon the shoulder formed by the countersink. The hole in the tie should be accurately bored, so that the distance between its bottom and the shoulder formed by the countersink will be exactly equal to the distance from the lower edge of the flange 11 to the bottom 10 of the bushing or sleeve. As a consequence, the sleeve will be firmly supported on the solid wood of the tie, and the flange 11 forms a good seat for the tie-plate 3, so that the latter cannot wear into the wood and destroy the tie mechanically.

The sleeve may be smooth on its exterior, as shown in Fig. 1, or may be provided with ribs or threads in any suitable way, said ribs either being annular, as shown at 12, Fig. 2, or arranged spirally and of any desired pitch. The hole in the tie should be slightly smaller than the sleeve, so that the latter will have a tight fit therein. It can be driven by means of a sledge and in driving will slightly compress the fibers of the wood, but not break the same. Consequently the fiber has a strong frictional grip on the sleeve, and on account of the comparatively large diameter thereof this will be sufficient to prevent the sleeve from working up and down.

The sleeve shown is simple and cheap of construction, is very strong, can be driven by means of a sledge, and has a strong frictional grip in the wood. It possesses many advantages over the ordinary method of fastening railway-rails, to wit: It increases the life of the tie due to the fact that the fibers of the wood are not broken and do not disintegrate no matter how often the rails may be taken up and re-laid. There is practically no wear on account of relaying rails or readjusting the track. The metal screw-spike working in the sleeve takes care of all of the wear that

would otherwise occur. The tie will be firmly held in contact with the rail-base instead of having the usual play due to the spike not having sufficient frictional hold in the wood. Its resistance against pulling out of the tie is largely due to its large outer bearing-surface, to the neat fit which it can have in its hole, thus not making it necessary to break the fiber, and to the ribs or threads formed on its outer surface. The sleeve forms a support for the rail-plate, so that the latter will not wear away the wood and destroy the tie mechanically. If the tie is treated with a preservative or if not so treated, the sleeve by reason of its neat fit in the wood and the flange at its upper end will prevent the water from getting down into the hole, and thus prevent the rotting of the tie or the leeching out of the preservative, if one is used, and will thus prevent destruction of the tie chemically. By means of this sleeve, the rails can be more easily laid to exact gage, since the holes for the sleeve can be bored exactly to gage.

25 What I claim is—

1. A screw bushing or sleeve for railway cross-ties comprising an internally-threaded solid metal sleeve having an outer surface adapting it to be driven into a hole in the tie and provided at its upper end with a flange for supporting the rail-plate.
2. A screw bushing or sleeve for railway cross-ties comprising an internally-threaded solid metal sleeve having an outer surface

adapting it to be driven into a hole in the tie 35 and having a closed lower end for resting on the bottom of the hole, and its upper end having a flange for supporting the rail-plate.

3. A railway-track structure comprising a wooden cross-tie provided with a hole countersunk at its top and a metal bushing or sleeve internally threaded and fitting in said hole with its lower end resting on the bottom of the hole, and having a flange fitting in the countersink and resting on the shoulder 45 formed thereby.

4. A railway-track structure comprising a wooden cross-tie provided with a hole countersunk at its top and a metal bushing or sleeve internally threaded and fitting in said 50 hole with its lower end resting on the bottom of the hole, having threads or projections on its outside to increase friction against pulling, and having a flange fitting in the countersink and resting on the shoulder formed 55 thereby.

5. A screw bushing or sleeve for railway cross-ties comprising an internally-threaded solid metal sleeve adapted to be driven into a hole in the tie and provided on its outer surface with projections for increasing friction 60 against vertical movement.

In testimony whereof I, the said ARNOLD STUCKI, have hereunto set my hand.

ARNOLD STUCKI.
